ATTORNEY

UNITED STATES PATENT OFFICE.

FREDERICK B. MALLORY, OF PORTLAND, OREGON.

DESIGN FOR A BLOCK SIDE.

44,016.

Specification for Design. Patented May 13, 1913.

Application filed April 7, 1913. Serial No. 759,542. Term of patent 14 years.

To all whom it may concern:

Be it known that I, FREDERICK B. MALLORY, a citizen of the United States, residing at Portland, in the county of Multnomah and State of Oregon, have invented a new, original, and ornamental Design for Block Sides, of which the following is a specification, reference being had to the accompanying drawing, forming part thereof, in which—

Figure 1 is a front view of my design; Fig. 2 is the reverse side of same; and Fig. 3 is an edge view of same.

The front view of my design consists of a circular web 1, with an extension 2, at the front thereof and two lugs 3 attached to said web at points diametrically opposite said extension, and ribs 4 tangent with the peripheral surface of said lugs and thence extending downwardly to the plane surface of boss 5 which is in the center of said web.

The circular portion of the reverse side of my design is concentric with the front side thereof with boss 6 in the center; said boss 6 being parallel with boss 5 on the front portion of the web; the tubular portion of said reverse side also having ribs 7 integral therewith. The remainder of reverse side is a plane surface 8 which is tangent with the periphery of lugs 3.

I claim:—

The ornamental design for a block-side substantially as shown and described.

In testimony whereof I hereunto affix my signature in the presence of two witnesses.

FREDERICK B. MALLORY.

Witnesses:

M. A. KELLIHER,
K. BRANDES.
